SIGNALING SYSTEM

Filed Feb. 1, 1929

Inventor:
Michiwo Taniguchi
by Charles E. Tullor
His Attorney

UNITED STATES PATENT OFFICE

MICHIWO TANIGUCHI, OF EBARAGUN, TOKYO-FU, JAPAN, ASSIGNOR TO GENERAL ELECTRIC COMPANY, A CORPORATION OF NEW YORK

SIGNALING SYSTEM

Application filed February 1, 1929, Serial No. 336,902, and in Japan April 19, 1928.

My invention relates to signaling systems and more particularly to means whereby signaling may be effected over wire lines which are used for other purposes.

5 One of the objects of my invention is to provide novel means whereby signaling such, for example, as telephone communication may be effected over lines which are used for control purposes such as the operation of re-
10 lays and the like without affecting the operation of the control devices.

Another object of my invention is to provide a novel switching arrangement whereby the above result may be accomplished and
15 whereby the line which is employed is alternately connected to the control devices and to the signaling devices.

Still another object of the invention is to provide means of the type indicated which is
20 sufficiently economical to install to permit its use in installations where the use of the wire line for signal or telephone purposes is only occasionally required and where the cost of the installation must necessarily be small.

25 The novel features which I believe to be characteristic of my invention are set forth with particularity in the appended claims. My invention itself, however, both as to its organization and method of operation together with further objects and advantages thereof may best be understood by reference to the following description taken in connection with the accompanying drawing which shows an embodiment of my invention:—

35 Referring to the drawing, I have represented at 1 a line which may connect two power stations A and B, which may comprise respectively a substation and central, or dispatcher's station of a power distribution system and which line may be used to control any desired control device 2, which may be, for example, the master starting relay of the remote station, in response to operation of a key 3 in the dispatcher's station B. In each
40 of the stations A and B are located telephone instruments 4 and 5, respectively.

45 In the substation A a control relay 6 is arranged to respond to current in the line 1 to connect the master relay 2 to a supply line
50 7 in the substation and thereby to control

that relay in response to current in line 1. This master relay 2 may also be connected to the supply line 7 through a switch 8. The control relay 6 and the telephone instrument 4 at the station A are arranged to be connected alternately to the line 1 by means of switch 9.

55 In the dispatcher's station B a magnetically operated switch 10 having an actuating winding 11 is arranged alternately to connect line 1 to a source of electro-motive force 12 and to the telephone instrument 5. The actuating winding 11 is arranged to be energized in response to operation of key 3.

60 The operation of the system is as follows: With the equipment in the position shown in the drawing it will be seen that a complete circuit extends from the source 12 through actuating winding 11, main contacts of switch 10, line 1, switch 9 in its upper position and the actuating winding of relay 6. Thus the actuating windings of both the switch 10 and relay 6 are energized and these devices are retained in the position shown in the drawing. Relay 6 thus connects the actuating winding of the master relay to the supply circuit 7 in the sub-station.

65 Assuming that the dispatcher at the central station desires to operate the master relay to its open circuit position, he will operate key 3 to its upper position thereby short-circuiting the actuating winding of switch 10 and causing this switch to operate under its bias to the position in which telephone instrument 5 is connected to the line and the supply source 12 is disconnected from the line. Actuating windings of relays 6 and 2 will then be deenergized thereby causing the relay 2 to operate to its open circuit position. When the operator desires to close the contacts of relay 2 he will operate key 3 to its lower position thereby energizing winding 11 and causing the switch 10 to interrupt the telephone circuit and to connect the supply source 12 to the line. As soon as key 3 is returned to its normal position the circuit of coil 11 is completed through line 1 rather than through the key with the result that switch 10 will remain in the position shown. Thus a momentary pressing of key 3 is sufficient for the

100

purpose. Relays 2 and 6 will now be operated to the closed position.

Assuming that an operator who visits the remote station A desires to speak with the operator in the station B, he will first operate switch 8 to its lower position, thereby connecting the actuating winding of master relay 2 to the supply circuit 7 through this switch. He will then operate switch 9 to the lower position. This operation will interrupt the circuit of actuating winding 11 thereby causing switch 10 to operate to the position in which the telephone instrument 5 is connected to the line. This operation will also deenergize relay 6 but operation of this relay will not now affect the master relay 2. The telephone signaling and conversion may then be had in the usual manner. When the telephone conversation is completed the operator at the station A will return switch 9 to its original position and the operator at station B will operate key 3 to its lower position thereby returning switch 10 to the position shown in the drawing. When this has been effected switch 8 may be returned to its normal position thereby again rendering the master relay 2 subject to the control of the operator in the station B. Thus it will be seen that a telephone conversation may be had over the line 1 without affecting the position of master relay 2, and that line 1 may be used practically independently both for control and signaling purposes.

While I have shown a particular embodiment of my invention it will of course be understood that I do not wish to be limited thereto since many modifications, both in the circuit arrangement and in the instrumentalities employed, may be made without departing from the spirit and scope of my invention as set forth in the appended claims.

What I claim as new and desire to secure by Letters Patent of the United States, is:

1. In combination, a dispatcher's station, a remote station, a line joining said stations, a control device in each station, a signal device in each station, switching means in each station for connecting said line alternately to the control devices and signal devices in the respective stations, and means responsive to operation of said switching means in one station to connect the line to the signal device in said one station and for operating the switching means in the other station over said line to connect the line to the signal device in said other station.

2. In combination, a dispatcher's station, a remote station, a line joining said stations, a source of current, signal means in both stations, switching means in the dispatcher's station for alternately connecting said line in circuit with said source and with the signal means in the dispatcher's station, means in the remote station responsive to current in said line, and means for controlling said

switching means without affecting said current responsive means and means for connecting the signal means in the remote station to the line.

3. In combination, a dispatcher's station, a remote station, a line joining said stations, means in the remote station responsive to current in said line, current supply means in the dispatcher's station, signal means in both stations, switching means biased to connect the line to the signal means in the dispatcher's station and arranged to connect the line to the current supply means in said station, means for retaining said switching means in condition to connect said line to said current supply means, and means in the remote station for releasing said retaining means and means for maintaining said current responsive means in the remote station in its instant condition when said retaining means is released.

4. In combination, a dispatcher's station, a remote station, a line joining said stations, current supply means, switching means in the dispatcher's station, biased to one position and having an actuating winding, a circuit controlled by said switching means in said one position, said switching means being arranged in another position thereof to connect said line in series with said actuating winding and said current supply means, whereby said switching means is retained in said other position, means in the remote station responsive to current in said line, whereby said means is controlled by said switching means in the dispatcher's station, and means in the remote station for interrupting said line thereby to actuate said switching means to said one position.

5. In combination, a dispatcher's station, a remote station, a line joining said stations, a signal device in each station, current supply means in the dispatcher's station, a device in the remote station, means responsive to current in said line for controlling said device, switching means in the remote station for alternately connecting said line to said current responsive means and to the signal device in said station, means for preventing operation of said switching means from affecting said device, and means in the dispatcher's station for connecting the line to said current supply means and responsive to operation of said switching means to connect the line to said signal device.

6. In combination, a dispatcher's station, a remote station, a line joining said stations, a signal device in each station, an additional device in the remote station, a circuit including said line, means in the dispatcher's station for controlling said additional device over said circuit, switching means for interrupting said circuit and for connecting said line to said signal devices, and means for preventing operation of said switching means

from affecting said additional device whereby said additional device is maintained in its instant condition when said current is interrupted.

5 In witness whereof, I have hereunto set my hand this fourteenth day of January, 1929.

MICHIWO TANIGUCHI.
